UNITED STATES PATENT OFFICE.

CHRISTY RICARD, OF WOONSOCKET, RHODE ISLAND.

SELF-THREADING SHUTTLE.

Application filed September 9, 1927. Serial No. 218,409.

This invention relates to an improved self-threading shuttle for looms and constitutes an improvement upon the shuttle described and claimed in my copending application

5 Serial Number 139,358 filed October 4, 1926.

In shuttles employed prior to the invention of that shown in my copending application referred to above, various means have been employed for preventing removal of the 10 thread from the forward end of the thread receiving passage, but none of the structures heretofore employed have combined with the means for preventing removal of the thread from the forward end of the thread receiving

15 passage a positive locking means for preventing removal of the thread from the rearward end of the thread receiving passage without which the provision of such means at the forward end of the thread receiving passage is 20 rendered ineffectual for the purpose intended, since in the start of the rearward movements of the shuttle a loop will be thrown off from the bobbin which will frequently be thrown forward a sufficient distance to release the thread from the holding means at 25 the forward end of the thread receiving passage.

My copending application referred to above provides means for obviating this difficulty by reason of the provision of a positive locking means at the rearward end of the thread receiving passage and the provision of a flexible holding member extending across the thread receiving passage adjacent 35 to the forward end thereof.

In the present application I employ the same holding means at the rearward end of the thread receiving passage as that described in my prior application above mentioned, but 40 have provided a slightly different and improved holding means at the forward end of the thread receiving passage.

One object of the present invention is to provide a self-threading shuttle of the character described which may be cheaply and easily constructed and which will positively lock the thread against removal from either end of the thread receiving passage.

Another object of my invention is the provision of a shuttle of this character which may be constructed almost entirely as a casting, and which contains the least possible number of elements liable to breakage or deterioration in use.

55 Other objects and advantages of the invention relate to various improved details of

construction and novel methods of operation as will be more fully set forth in the detailed description to follow:

Referring to the drawings:

Fig. 1 is a perspective view of a portion of a self-threading shuttle embodying the present invention, and illustrating the position of the bobbin therein.

Fig. 2 is an enlarged sectional view, taken 65 along the line 2—2 of Fig. 1.

Fig. 3 is a perspective view of the thread block illustrating the thread locking means employed at the forward end of the thread receiving passage, and

Fig. 4 is a detail sectional view, taken along the line 4—4 of Fig. 3.

In the embodiment of the invention illustrated herewith, the shuttle body 1 is of the usual construction and is provided with a 75 chamber 2 within which is located a bobbin 3 carrying the thread 4 as is usual in devices of this character.

A thread block 5, preferably formed of cast metal, is fitted within a suitably shaped opening formed in the end of the shuttle body, and is provided with a thread receiving passage 6 communicating with and forming an extension of the thread receiving passage 7 formed in the shuttle body. The thread receiving passage through the thread block 5 and shuttle body is substantially straight throughout its length, and a flexible blade 8 is anchored in one side of the thread block 5 adjacent to the rearward end of the thread 90 receiving passage, as indicated at 9, and is provided with a curved end portion which is adapted to lie within a circular groove 10 formed upon the inner face of the thread receiving passage.

As shown in Fig. 1, the flexible blade 8 which provides a positive locking for preventing escape of the thread from the thread receiving passage is located adjacent to the rearward or bobbin end of said passage.

The thread block 5 may be formed entirely from cast metal with the exception of the flexible blade 8, and the thread receiving passage 6 formed therein communicates with a side delivery eye 12 formed in one side of the bobbin through which the thread normally passes during the reciprocation of the shuttle.

The inner face of one side wall 13 of the casting is provided with a shallow longitudinal depression 14 located adjacent to the forward end of the thread receiving passage

6, and a projection 15 extends inwardly across the thread receiving passage and into the depression 14, the projection being curved downwardly near its end to permit the 5 thread 4 to readily slide downwardly there-over into the thread receiving passage in threading the shuttle. When the thread has passed below the projection 15, it is positively held against removal by direct upward movement by the projection 15, the end of which enters the depression 14, and the provision of the locking means 8 adjacent to the rearward end of the thread receiving passage prevents the thread from looping forward from the 10 bobbin so as to be drawn forwardly over the projection 15. The provision of the locking means at the rearward end of the thread receiving passage taken together with the thread holding means at the forward end of 15 said passage thus positively prevent the escape of the thread from either end of the thread receiving passage and insure the retention of the same in the passage at all times. In placing the thread in the passage it is only necessary to lay it across the thread block, and, 20 since the passage is straight, the tension will draw the thread downwardly into the passage under the flexible blade 8 and down over the downwardly sloping surface of the projecting tip 15, and on the return movement of the 25 shuttle after replenishment the thread will pass through the side delivery eye 12 adjacent to the groove 16 in the shuttle.

The construction shown herein is adapted 30 to draw the thread downwardly into the thread receiving passage on the first pick after replenishment when the thread is drawn under the flexible blade 8 and over the sloping end of the projection 15. It is then impossible for the thread to escape from the 35 passage as it cannot be drawn directly upwardly

past the projection 15 and the flexible blade 8 will hold it from looping forwardly from the bobbin past the end of the projection 15. 45 By utilizing the projection 15 extending into the depression 14 at the forward end of the thread receiving passage, instead of a flexible member, the structure may be formed by casting, all except the flexible blade 8, and the liability of an exposed flexible member at the 50 front of the thread receiving passage to becoming bent or otherwise injured is entirely obviated. While the present improvement is best adapted for use with the form of thread 55 block having a straight thread receiving passage, as shown, it may be applied to and used in connection with any of the usual types of thread blocks now generally employed.

What I claim is:—

In a self-threading shuttle, a thread block 60 having a longitudinal thread receiving passage provided adjacent to one end thereof with a transverse groove, a curved resilient thread lock located within the passage in said block adjacent to one end of said passage so positioned as to permit insertion of the thread beneath the curved thread lock by downward movement of the thread within the passage and having the end thereof lying within the groove formed in the wall of said 65 passage, a portion of said thread block forming one wall of said thread receiving passage and provided with a depression located adjacent to the opposite end of said passage from the curved thread lock, and a downwardly inclined projection extending across said passage and having the end thereof located within the depression.

In testimony whereof I have affixed my signature.

CHRISTY RICARD
